W. CLEVELAND & J. R. OCKINGA.
RADIATOR.

APPLICATION FILED FEB. 24, 1913.

1,087,922.

Patented Feb. 24, 1914.

UNITED STATES PATENT OFFICE.

WILLIAM CLEVELAND AND JACOB R. OCKINGA, OF GLENVILLE, NEBRASKA.

RADIATOR.

1,087,922.

Specification of Letters Patent. Patented Feb. 24, 1914.

Application filed February 24, 1913. Serial No. 750,283.

To all whom it may concern:

Be it known that we, WILLIAM CLEVELAND and JACOB R. OCKINGA, citizens of the United States, residing at Glenville, in the county of Clay and State of Nebraska, have invented certain new and useful Improvements in Radiators, of which the following is a specification, reference being had to the accompanying drawings.

10 This invention relates to improvements in radiators adapted for use upon automobiles or the like, for cooling the water which is circulated through the water jackets of the engine cylinders.

15 An object of this invention is the provision of a radiator comprising a plurality of sections detachably connected together, whereby the radiator may be readily taken apart when it is desired to repair the same 20 or replace any of the water tubes.

25 A still further object of this invention is the provision of novel means whereby tight joints are provided between the several sections to prevent the water from escaping from the radiator.

30 With these and other objects in view, our invention consists in certain novel constructions, combinations, and arrangements of parts, to be hereinafter more fully described, claimed and illustrated in the accompanying drawings, in which—

35 Figure 1 is a front elevation showing the sections of the radiator disconnected; Fig. 2 is a fragmentary vertical section of the sections when connected; Fig. 3 is a perspective view of the means for securing the lower ends of the tubes to the lower wall of the intermediate or central section of the radiator.

40 Referring more particularly to the drawings, the letter A designates the upper section of the radiator, B, the intermediate or central section, and C, the lower section thereof. The central section B comprises 45 end walls 1, a top wall 2 and a bottom wall 3, the end walls having connected thereto a plurality of horizontal radiating plates 4 which are spaced vertically and are provided with a plurality of vertically aligned 50 openings 5. The top wall 2 of the central section is provided with a plurality of threaded openings 6 which are disposed in vertical alinement with the openings 5 in the plates 4, and the bottom wall 3 is also 55 provided with a plurality of threaded openings 7 disposed in vertical alinement with

the openings in the plates, the openings 7 in the bottom wall of the section being slightly larger in diameter than the openings in the top wall thereof. Threadably connected in each of the openings 7 in the bottom wall 3 is an exteriorly and interiorly threaded sleeve 8, the exterior threads of each sleeve being adapted to engage the threads of the opening, the sleeves being formed with enlarged heads 9 at their upper end which are adapted to rest against the upper face of the bottom wall 3 to limit the movement of the sleeves. The enlarged head 9 of each of the sleeves is formed with an inwardly extending annular flange 10, which is adapted to form a seat for a gasket 11. Disposed through the sleeves 8 and the aligned openings in the plates 4, are a plurality of water tubes 12 which are threaded as at 13, at 75 their upper ends for engagement with the threaded openings 6 in the upper wall of the section. To provide a water tight joint between each of the openings 7 and the lower ends of the tubes 12, an exteriorly threaded 80 collar 14 is provided for threaded engagement with the interior threads of the sleeve 8 in each opening, the inner periphery of the collar being adapted to frictionally engage the outer periphery of the lower end of 85 the pipe 12, and the edge of the collar being adapted to bear against the washer 11 to spread the same and force it against the periphery of the tube. The end members 1 of the intermediate section are formed 90 of spaced walls 15, and horizontal and apertured supporting plates 16 are disposed between the spaced walls 15 and project outwardly from the ends opposite of the section B whereby the radiator may be secured to 95 the frame of the automobile.

The upper section A comprises a bottomless water chamber which is provided with an inlet pipe 17 through which the water from the jackets of the engine enters, the 100 chamber being also provided with a filling pipe 18 which is provided with a suitable cap 19. The opposite ends of the upper section A are provided with suitable transversely extending angular boxings 20, the 105 boxings being of a width substantially the distance between the spaced walls 15 of the intermediate section, and secured to the inner walls of the boxings and the side walls of the upper section above the lower edge 110 thereof is an inwardly extending flange or gasket seat 21 against which is seated

a gasket 22. Extending downwardly from the boxings 20 are connecting bolts 23 which are adapted to extend through the plates 16 between the walls 15 of the central section and project below the bottom of the central section.

The lower section C of the radiator comprises a top open water chamber and is provided with an outlet pipe 24 which leads to 10 the water jackets of the engine, the lower section being provided with spaced end walls 25, the outer walls of which are provided with upwardly extending flanges 26 which are adapted to engage the outer end walls 15 of the central section. Formed on the inner end walls 25 and the side walls of the bottom section is an inwardly extending flange 27, the flange 27 being spaced slightly from the upper edge of the section to form 20 a seat for a gasket 28. When the sections are connected, the gasket 22 is disposed between the flange 21 of the upper section and the upper wall of the intermediate section, to form a tight joint between the sections, 25 and the gasket 28 is disposed between the flange 27 of the lower section and the lower wall of the upper section, to form a tight joint between the lower section and the intermediate section. The lower ends of the 30 bolts 23 project through the bottom wall of the lower section, and threaded upon the lower ends of the bolts are suitable wing nuts 29 which are adapted to bear against the lower wall of the bottom section to se- 35 cure the sections of the radiator together. Should any of the tubes 12 become broken, it will only be necessary to remove the lower section of the radiator, whereupon the collars 14 may be removed from the lower ends 40 of the broken tubes so that the tubes may be rotated to unthread the upper ends thereof from engagement with the threaded openings 6 in the upper wall of the intermediate section whereupon the tubes may be removed 45 and new ones replaced.

It will be seen that the water circulates through the radiator in the ordinary manner, that is, it enters the upper water chamber, whereupon it flows through the tubes 12 and then flows back to the water jackets 50 through the outlet pipe 24.

Having thus fully described our invention what we claim and desire to secure by Letters Patent is:

A device of the character described in- 55 cluding an upper section, an intermediate section, and a lower section, said upper section being provided with boxings on oppo- site sides and with inwardly directed flanges, the intermediate section having spaced inner 60 and outer walls at opposite sides thereof, said outer walls having their upper ends terminating below the upper ends of the inner walls, said lower section having spaced walls at opposite sides thereof and adapted 65 to overlap the walls of the intermediate section, the inwardly directed flanges of the upper section being adapted to rest upon the top of the intermediate section, while the boxings of such upper section are adapted 70 to overlap the inner walls of the spaced sides of the intermediate section and rest upon the outer walls, the inner wall of the lower section being provided with an inwardly directed flange on which the base of the intermediate 75 section is adapted to rest, and clamping means positioned between the spaced walls of the intermediate section and being oper- atively engaged with the boxings of the upper section and with the lower section where- 80 by the several sections are maintained in op- erative relation.

In testimony whereof we hereunto affix our signatures in the presence of two wit- nesses.

WILLIAM CLEVELAND.
JACOB R. OCKINGA.
